UNITED STATES PATENT OFFICE.

HERBERT G. THOMSON, OF NEW YORK, N. Y.

HAND TRUCK.

Application filed October 24, 1924. Serial No. 745,554.

To all whom it may concern:

Be it known that I, HERBERT G. THOMSON, a citizen of the United States, and resident of the city of New York, borough of Manhattan, in the county of New York and State of New York, have invented certain new and useful Improvements in Hand Trucks, of which the following is a specification.

This invention relates to hand trucks, its object being to provide a metal truck of relatively light weight possessing the merits of cheapness, strength and durability.

The invention, generally stated, comprehends a truck having side frame members composed of U-bars of rolled or pressed steel; a nose member having integral supporting limbs fitted into the channels of the bars; a fixed axle; wheels journaled thereon, and novel supporting brackets for the axle, each bracket comprising a single piece of metal struck up to present a substantial body portion having an upper angular flange member which underlies the said bars and the limbs of the nose member and is bolted thereto, and having a lower recess into which the adjacent end of the axle extends, said recess being formed by a struck-out portion of the body and affording an angular supporting and steadyng member to which the axle is securely bolted, together with various details of construction, all of which will be hereinafter described and claimed.

In the drawings—

Figure 1 is a plan of a hand truck embodying my invention.

Fig. 2 is a side elevation of the truck.

Fig. 3 is a partial transverse section through one side of the truck, as on the line 3—3 of Fig. 2.

Fig. 4 is a similar section through one of the handles, as on the line 4—4 of Fig. 2.

Fig. 5 is a perspective view of one of the sheet metal axle-brackets.

Referring to the drawings, 6 designates longitudinal frame members composed of U-bars of rolled or pressed steel having downwardly curved upper portions bent to circular cross section to constitute integral handles 7. These bars are connected at intervals by means of transverse supporting straps 8 which are bolted at their ends to the respective bars to afford therewith a substantial truck frame. Into the open lower portions of the frame bars 6 extend the

angular legs 9 of a nose member 10, which legs are of such form in cross-section as to fit snugly into the lower portions of the bars, distance pieces, as 11, being interposed between the legs and the tops of the bars.

Depending brackets 12 of novel construction are arranged to support, firmly and rigidly, the ends of the axle 13 on which the wheels 14 are journaled. Each bracket 65 comprises a body portion of generally triangular shape having along its upper edge an inturned horizontal flange 15 of substantial length and width and having in its lower or apex portion a polygonal recess 16 70 from the upper edge of which projects an inturned horizontal tongue 17, the whole being struck up from a single piece of sheet steel. Each axle bracket is so arranged that its flange 15 underlies and bears firmly 75 against the adjacent frame bar and the associated leg 9 of the nose member, and the several parts just mentioned are secured together by bolts 18, or the like, passing therethrough and through the confined distance 80 pieces 11.

As herein illustrated the recesses 16 are shaped correspondingly with the cross section of the main body of the axle 13 so as to receive and support the axle while the 85 tongues 17 overhang and bear squarely upon the top of the latter. These tongues 17 are secured to the axle, as by bolts 19, thus insuring a rigid and stable connection between the axle and the brackets. 90

By the construction above described it will be seen that the depending axle brackets are effectually reinforced and strengthened by their angularly bent upper flanges; that such flanges afford substantial bearing 95 surfaces for the brackets against the lower edges of the frame bars and also provide, in conjunction with the distance pieces and bolts, simple and effective clamping and steadyng members for the associated parts. Moreover, the recesses 16 of the brackets, 100 plus the angular tongues, ensure firm and rigid supports and connections for the axle and the brackets. Consequently my invention provides a simple and inexpensive hand truck of great strength and relative lightness. 105

I claim—

1. A truck comprising spaced-apart U-shaped frame bars of rolled or pressed steel, 110 a nose member having legs fitted into the channels of the bars, an axle, wheels jour-

naled thereon, axle brackets each comprising a single piece of stamped metal having a body portion provided with a lower recess, an upper inturned supporting and 5 clamping flange which underlies and bears against the adjacent frame bar and the associated leg of the nose member, and a tongue projecting laterally from the top of the recess, said recess snugly receiving, and 10 said tongue overhanging, the axle, means securing the flanges to the adjacent frame bars and legs, and means securing the axle to the overhanging tongues.

2. A truck comprising spaced-apart 15 U-shaped from bars of rolled or pressed steel, a nose member having legs fitted into the channels of the bars, distance pieces between the said legs and the tops of the respective bars, an axle, wheels journaled 20 thereon, axle brackets each comprising a single piece of stamped metal having a body portion provided with a polygonal recess, an upper inturned supporting and clamping

flange which underlies the adjacent frame bar and the associated leg of the nose member, and a tongue projecting laterally from the top of the recess, said recess snugly receiving, and said tongue overhanging, the axle, bolts securing together the adjacent flanges, frame bars and distance pieces, and 25 bolts securing the axle to the overhanging tongues. 30

3. The herein described axle bracket for wheeled hand trucks, comprising a single piece of stamped metal shaped to provide a body portion having a lower recess, an upper angular supporting portion, and a tongue projecting laterally from the top of the recess, said recess being adapted to receive the axle of the truck and said tongue being 35 adapted to overhang and be secured to the axle. 40

Signed at New York, in the county and State of New York, this 22nd day of October A. D. 1924.

HERBERT G. THOMSON.
